UNITED STATES PATENT OFFICE.

OTTO PARKER HALLOCK, OF MATTITUCK, NEW YORK.

POTATO-SORTER.

SPECIFICATION forming part of Letters Patent No. 768,989, dated August 30, 1904.

Application filed September 19, 1903. Serial No. 173,792. (No model.)

To all whom it may concern:

Be it known that I, OTTO PARKER HALLOCK, a citizen of the United States, and a resident of Mattituck, in the county of Suffolk and State 5 of New York, have invented a new and Improved Potato-Sorter, of which the following is a full, clear, and exact description.

The object of the invention is to provide a new and improved potato-sorter which is simple and durable in construction, very effective in operation, and arranged to sort the large potatoes from the smaller ones and to separate the dirt from the large potatoes.

The invention consists of novel features and 15 parts and combinations of the same, as will be more fully described hereinafter and then pointed out in the claims.

A practical embodiment of the invention is represented in the accompanying drawings, 20 forming a part of this specification, in which similar characters of reference indicate corresponding parts in both views.

Figure 1 is a sectional side elevation of the improvement, and Fig. 2 is a plan view of the 25 same.

On the upper ends of legs A are secured the sides B of a box-like structure having cross-bars B' B² for connecting the ends of the sides B with each other. On the top of the sides B 30 and at the middle thereof is secured a hopper C, into which the potatoes to be assorted are dumped, and below this hopper, between the sides B B², is arranged a double grate D, consisting of a cross-bar D' and two sets of grate-bars D² D³, extending longitudinally and connecting the grate cross-bar D' with the box cross-bars B' B².

The sets of grate-bars D² D³ extend downwardly in opposite directions from the cross-bar D' to the cross-bars B' B², so that the potatoes passing from the hopper C onto the grate D are separated at the cross-bar D' into two streams, running down by their own gravity in opposite directions on the sets of grate-bars D² D³.

The grate-bars in each set are spaced apart to allow the smaller potatoes to drop down be-

tween adjacent grate-bars, while the larger potatoes roll down the grate-bars toward the lower ends thereof. The smaller potatoes and 50 the dirt dropping through between the grate-bars D² D³ fall into a hopper E, preferably made of canvas or like fabric material and attached at its ends and sides to the cross-bars B' B² and the sides B of the box-like structure. 55 The middle of the hopper E is provided with an opening E', through which the smaller potatoes and the dirt can pass and drop into a basket or other receptacle placed on the floor below the said hopper E.

The large potatoes are adapted to pass into bags G, each held on a bag-support formed by pins F, projecting from the outer faces of the sides B, at the ends thereof, (see Fig. 2,) for receiving the sides of the bag, and the top 65 edge of the bag is adapted to be hooked onto the pointed ends of arms F', mounted to swing on the sides B, so that the mouth of the bag extends over the outlets of the box-like structure for the potatoes to roll from the grate-bars D² D³ over the cross-bars B' B² into the bag.

Each set of grate-bars is provided near its lower end with a retaining device H for holding the large potatoes temporarily until a sufficient quantity has accumulated for discharging the same into the bag. This retaining device H consists, essentially, of a shaft H', extending transversely under the corresponding set of cross-bars D² and D³, and the ends of 75 the shaft are journaled in the sides B of the box-like structure. From each shaft H' extend prongs H², curved upwardly and outwardly and extending between adjacent cross-bars D² or D³, as plainly indicated in the 80 drawings. A spring I, attached to a leg A, is connected with an eye H³ on the rear end of the corresponding shaft H', so as to hold the said shaft and its prongs H² normally in a retaining position—that is, with the curved 85 ends of the prongs H² extending above the grate-bars D² D³ to retain the potatoes rolling down the said grate-bars.

Each of the shafts H' is provided with an

outwardly-extending arm H^4 , connected by a link J with a treadle K , fulcrumed at K' on one of the legs A , and the said treadle K extends through a guide L , attached to another leg and serving to limit the upward and downward movement of the treadle K , which is normally, however, held in an uppermost position by the action of the corresponding spring I .

10 When a sufficient quantity of potatoes has accumulated on a retainer H , then the operator presses the corresponding treadle K so as to impart a swinging motion to the shaft H' to swing the prongs H^2 downward below the corresponding set of grate-bars D^2 D^3 to release the accumulated potatoes and allow the same to travel down into the bag G . As soon as the operator releases the pressure on the treadle K the retaining device returns to 15 its former position by the action of the spring I to retain another load of large potatoes passing down the corresponding set of grate-bars D^2 and D^3 .

By the arrangement described a single operator can readily handle a large quantity of 20 potatoes, as the retaining devices H are normally in an uppermost position and can be actuated successively by the operator passing from one end of the machine to the other, and 25 when one bag is filled the operator can readily remove the filled bag and replace the same by an empty one without the potatoes rolling from the machine to the ground.

The top of the grate cross-bar D' is rounded 30 off, as plainly shown in the drawings, so as to readily separate the potatoes from the hopper C into two streams.

Having thus described my invention, I claim as new and desire to secure by Letters Patent—

40 1. A potato-sorter comprising a hopper, an inclined grate having spaced cross-bars for the potatoes filled into the hopper to travel down by gravity, a temporary retainer pivotally supported underneath said grate and having fingers extending upwardly between the grate-bars above the upper side of said bars for retaining the potatoes on the bars, means for normally holding said retainer in its operative position with the fingers extending above the 45 bars to retain the potatoes on the grate, and manual means connected with the frame of the device for withdrawing the fingers to permit the potatoes to move on.

50 2. A potato-sorter, comprising a hopper, an inclined grate having spaced cross-bars for the potatoes filled into the hopper to travel down by gravity, a temporary retainer located underneath the grate at the lower side thereof and having fingers extending upwardly through 55 the bars for retaining the potatoes on the bars, a spring for normally holding said retainer in its uppermost position, and a foot-lever for

withdrawing said projecting fingers of the retainer when desired.

3. A potato-sorter comprising a hopper, a grate having two sets of spaced cross-bars, extending downwardly in opposite directions from the middle of the grate, the said middle of the grate being located directly below the middle of the hopper, for the potatoes filled 70 into the hopper to separate on the middle or apex of the grate and travel by their own gravity in two streams down the grate-bars, and a retainer at the lower end of each set of grate-bars, for temporarily retaining the potatoes rolling down the grate-bars, as set forth. 75

4. A potato-sorter comprising a hopper, a grate having two sets of spaced cross-bars, extending downwardly in opposite directions from the middle of the grate, the said middle 80 of the grate being located directly below the middle of the hopper, for the potatoes filled into the hopper to separate on the middle or apex of the grate and travel by their own gravity in two streams down the grate-bars, 85 a retainer at the lower end of each set of grate-bars, for temporarily retaining the potatoes rolling down the grate-bars, and manually-controlled means for actuating each retainer independent of the other, as set forth. 90

5. A potato-sorter comprising a hopper, a grate having two sets of spaced cross-bars, extending downwardly in opposite directions from the middle of the grate, the said middle 95 of the grate being located directly below the middle of the hopper, for the potatoes filled into the hopper to separate on the middle or apex of the grate, and travel by their own gravity in two streams down the grate-bars, and a retainer at the lower end of each set of 100 grate-bars, for temporarily retaining the potatoes rolling down the grate-bars, the said retainer consisting of a spring-pressed rock-shaft extending transversely under the grate-bars, near the lower ends thereof, and curved 105 prongs secured on the said shaft and adapted to extend between adjacent cross-bars, to reach with their free ends above the grate-bars, as set forth.

6. A potato-sorter comprising a hopper, a 110 grate having two sets of spaced cross-bars, extending downwardly in opposite directions from the middle of the grate, the said middle of the grate being located directly below the middle of the hopper, for the potatoes filled 115 into the hopper to separate on the middle or apex of the grate and travel by their own gravity in two streams down the grate-bars, a retainer at the lower end of each set of grate-bars, for temporarily retaining the potatoes rolling down the grate-bars, the said retainer consisting of a spring-pressed rock-shaft extending transversely under the grate-bars, near the lower ends thereof and curved 120

prongs secured on the said shaft and adapted to extend between adjacent cross-bars, to reach with their free ends above the grate-bars, and a treadle mechanism connected with each rock-shaft, for actuating the corresponding retainer, as set forth.

In testimony whereof I have signed my name

to this specification in the presence of two subscribing witnesses.

OTTO PARKER HALLOCK.
